CONTAINER

Charles McMahon, Philadelphia, Pa.

Application May 12, 1932. Serial No. 610,770

8 Claims. (Cl. 229—1.5)

This invention relates to containers, and has for an object to provide a container of new and improved type composed of transparent sheet material, and filled and closed in an improved manner.

A further object of the invention is to provide a transparent container of approximately conical form, with means facilitating the filling of the container from the base of the cone, and providing means at the apex of the cone for discharging the contents.

A further object of the invention is to provide a container which includes in the base of the conical structure a shouldered ring into which a disk is inserted for closing, and with a closure for the apex of the cone for handling.

The invention therefore comprises a conically shaped container of transparent flexible material having its apex folded over and secured, and a base formed as a shouldered ring with a disk inserted into the ring and seated upon the shoulder as a closure.

The drawing illustrates an embodiment of the invention and the views therein are as follows:

Figure 1 is a view of the improved container in elevation.

Figure 2 is a view of the container in vertical diametrical section, taken on line 2—2 of Figure 1, and

Figure 3 is an inverted plan view with part broken away.

Like characters of reference indicate corresponding parts throughout the several views.

The improved container, which forms the subject matter of this application is especially designed for marketing and containing such liquids as milk, although it is not limited in its utility to such material. It comprises a base 10, composed of any approved material. In practice, it has been found desirable to mold this base of some fibrous material, such as paper pulp, but the invention is in no way limited to this exact material. The ring is reduced to form a shoulder 11, with upstanding part 12. Upon the upstanding part 12, which is preferably though not necessarily tapered, a conical body 13 is erected. Preferably, this conical body will be made of transparent sheet material of which a number are already well known upon the market. It may be made in any manner found desirable or convenient in manufacture, but as shown in the drawing, it is overlapped at 14 and the edges secured in any approved manner as by heating the material itself or by the use of an adhesive.

The upper or tapered end is folded over as shown at 15 and is secured also by heat or adhesive, and in addition, a member 16 is applied thereto. This latter member may be a staple, an eyelet, or any form of fastening member and is designed more especially in assisting in handling the container when filled, but also prevents the adhering parts from separating.

Seated upon the shoulder 11 is a disk 17 which may be made of any sheet material found desirable. For filling the container, therefore, it is inverted and filled from the base and when filled, the disk 17 forced to seat in the usual well known manner to close the container by such disk closure.

For discharging the contents of the container, the apex below the folded end 15 is cut off and the contents poured out. If only part of the contents are poured out, the top is then twisted to form a tight or relatively tight closure. In this manner, a part only of the contents may be used and the container closed for future use.

Of course, the container herein illustrated may be modified and changed in various ways without departing from the invention herein set forth and hereinafter claimed.

The invention is hereby claimed as follows:

1. A container comprising an internally shouldered ring, a conical body erected upon the exterior of the ring, means closing the apex of the conical body, and a disk for closing the ring upon the shoulder.

2. A container comprising a base composed as a ring having an internally inset shoulder and an upstanding part, a conical body of transparent sheet material erected upon and secured to the exterior of said upstanding part, and a disk closure forced into the ring and seated upon the shoulder.

3. A container comprising an annular base having an annular shoulder therein, a conical transparent body built upon the exterior of the base and extending thereabove, the apex of said conical body being sealed and provided with a fastening member, and a disk closure for the annular base adapted to be forced to seat upon the shoulder.

4. A container comprising a ring having internal and external rabbets, a container body seated in one rabbet, and a closure seated in another rabbet.

5. A container comprising a ring having internal and external rabbets, a terete container body seated in one rabbet, and a closure seated in another rabbet.

6. A container comprising a base ring having an upper external rabbet, and a lower internal rabbet, a terete container body seated in the external rabbet, and a disk seated in the internal rabbet and closing the container.

7. A container comprising a base ring having an external rabbet with a conically inclined side wall, and an internal rabbet, a terete container body seated in the external rabbet and coinciding with the taper of the wall, and a disk seated in the internal rabbet and closing the container.

in the internal rabbet and closing the container.

8. A container comprising a base ring having an upper external rabbet with a conically inclined side wall, and a lower internal rabbet, a terete container body seated in the external rabbet and coinciding with the taper of the wall, and a disk seated in the internal rabbet and closing the container.
